HOLDING DEVICE

Harry M. Morrow, Canton, Ohio, assignor to The Bowdil Company

Application February 12, 1943, Serial No. 475,637

6 Claims. (CL. 74—251)

My invention relates in general to a holding means and more particularly to a holding means for opposing the disengagement of a pin from the aligned holes of a hinged connection.

I have illustrated my invention in connection with a coal cutting chain having pivotally connected elements connected together by a pin, but it is to be understood that my invention may be useful in connection with other types of pivot or hinge connections.

An object of my invention is the provision of a holding means which opposes disengagement of the pin from a pivot or hinge connection and which may be readily applied without materially changing the construction and design of the connection parts.

Another object of my invention is the provision of a holding means for opposing the disengagement of a pin in a hinge or pivot connection in which the holding means does not interfere with the ready assembly of the pin in the aligned holes of the connected parts.

Another object of my invention is the provision of a holding means for a pin in a pivot or hinge connection whereby the pin may be knocked out by heavily striking the same with a hammer or other suitable tool.

Another object of my invention is the provision of a holding means for a pin of a pivot or hinge connection which obviates the necessity of snugly pressing the pin in the aligned holes of the connected parts for the full length of the pin.

Another object of my invention is the provision of a holding means for a pin in a pivot or hinge connection having a bushing whereby the holding means operates to keep the bushing from turning as well as to oppose the disengagement of the pin from the bushing.

Another object of my invention is the provision of a holding means for securing a pin in an opening.

Another object of my invention is the provision of a holding means in the form of a rivet having a head which keys or locks a pin in an opening.

Other objects and a fuller understanding of my invention may be had by referring to the following description and claims taken in combination with the accompanying drawings, in which:

Figure 1 is a side elevational view of two hinged elements of a mining machine chain embodying the holding means constituting my invention;

Figure 2 is an enlarged cross-sectional and fragmentary view taken along the line 2—2 of Figure 1 and shows the connecting pin and my holding means in their assembled position;

Figure 3 is the side elevational view of my hold-

ing means which is in the form of a rivet, the rivet being shown in its upset position in Figure 2 of the assembled connection;

Figure 4 is a view similar to Figure 2 and shows the position of the rivet and the connecting pin during the initial stages of the assembly thereof in the chain elements;

Figure 5 is a view similar to Figures 2 and 4 and shows the connecting pin fully pressed into the aligned openings of the connected elements of the chain with the rivet ready for an upsetting operation;

Figure 6 is an enlarged fragmentary view showing principally the main aligned openings of the connecting elements of the chain, together with the secondary opening through which the rivet passes;

Figure 7 is an enlarged cross-sectional and fragmentary view taken along the line 2—2 of Figure 1 and showing the eye-portion of the chain connection;

Figure 8 is a top view of the connecting pin;

Figure 9 is a cross-sectional view of the pin taken along the line 9—9 of Figure 8;

Figure 10 is a top view of the rivet shown in Figure 3;

Figure 11 is a view similar to Figure 2, but shows in addition thereto a bushing having a notch in one edge thereof into which a small portion of the holding rivet is depressed to keep the bushing from turning;

Figure 12 is a side view of the notched bushing used in Figure 11;

Figure 13 is a view similar to Figure 4, but shows a pin having a key-way in the side thereof to receive the head of the holding rivet;

Figure 14 is a view of the device in Figure 13, being similar to the location of the parts in Figure 5, and shows the head of the holding rivet locked in the key-way in the side of the pin;

Figure 15 is another view of the device in Figure 13, being similar to the location of the parts in Figure 2, and shows the holding rivet in its final upset condition for holding the pin in the hinge connection;

Figure 16 is a side view of the pin used in Figures 13, 14 and 15, a portion being shown in section to illustrate the key-way;

Figure 17 is a plan view of the pin in Figure 16;

Figure 18 is a side view of the holding rivet used in Figures 13, 14 and 15; and

Figure 19 is a plan view of the holding rivet in Figure 18.

With reference to Figure 1 of the drawings, I illustrate two connected elements of a mining machine cutting chain illustrated generally by the

reference character 15. The chain is adapted to carry a suitable cutting bit 16 for cutting coal or other material. The bottom portion of the connected elements of the chain may be referred to as the chain portion and is designated generally by the reference character 17. In the drawings, the chain portions are substantially identical, in that each portion comprises a yoke having two side members 18 and 19 and an eye-portion 20 which fits between the two side members 18 and 19 of the yoke portion. The chain may be driven by a suitable driving sprocket indicated by the reference character 21. The two side members 18 and 19 of the yoke portion and the eye-portion 20 are provided respectively with main openings 28, 29 and 30 arranged to receive a connecting pin 23. A bushing or bearing 22 fits within the opening 30 of the eye-portion 20 and in my embodiment of the invention the bushing or bearing 22 is free to rotate about the pin 23 and within the opening 30 in the eye-portion 20.

The holding means for opposing disengagement of the pin 23 from the aligned openings of the side members 18 and 19 of the yoke portion and of the eye-portion 20, is in the form of a rivet 24 and has its head 25 cut away on one side as shown in Figures 3 and 10. The stem of the rivet 24 passes through a secondary opening 27 which forms a bay with respect to the main opening 28 in the side member 18 of the yoke portion of the chain.

As shown in Figure 2, 4 and 5, the underneath side of the side member 18 in the vicinity of the secondary opening 27 is provided with a tapered recess to receive the head 25 of the rivet, with the result that the exposed end of the head of the rivet lies substantially flush with the underneath side of the side member 18. The eye-portion 20 of the chain forms an anvil upon which the head of the rivet may rest while the stem is being upset. The top of the side member 18 and the top of the connecting pin 23 in the vicinity surrounding the stem of the rivet 24 is provided with a recess 26 to receive the upset end of the rivet 24.

In assembling the two chain elements, the rivet 24 is first inserted in the secondary opening 27 and is held therein while the eye-portion 20 and the bushing 22 are inserted between the side members 18 and 19 of the yoke portion of the chain elements. The eye-portion 20 and the bushing 22 are slid under the head 25 of the rivet 24 until the bushing 22 is properly aligned with reference to the openings 28 and 29 in the side members 18 and 19 of the yoke. The pin 23 is next inserted in the bushing 22 as indicated in Figure 4. At this point of the assembly, the pin 23 is pressed into the openings 28 and 29 by any suitable pressing means. That is to say, the pin 23 is snugly pressed into the openings 28 and 29, while it may freely pass through the opening in the bushing 22. Inasmuch as the bushing 22 is free to rotate about the pin 23 and in the opening 30 of the eye-portion 20, the wear upon the bushing 22 is completely around the bushing instead of being localized at one place as would be the case if the bushing 22 were not permitted to rotate. Accordingly, the elongation of the chain resulting from the wear of each bushing is reduced to a minimum.

After the pin 23 has been pressed into the side members 18 and 19 as shown in Figure 5, the next operation is to upset the stem of the rivet 24 as shown in Figure 2. A portion of the upset stem of the rivet overlaps the recess 26 in the exposed

end of the pin 23 and thus opposes disengagement of the pin 23 from the aligned openings of the pivot connection. In actual service the overlapping portion of the upset end of the rivet is effective in preventing the pin 23 from becoming disengaged. However, in the event that it becomes necessary to disconnect the chain for repair or replacement of parts, the pin 23 may be knocked out of the aligned openings by striking the same with a hammer or other suitable tool. In driving out the pin 23 with the hammer, the overlapping portion of the rivet is pushed back to allow the pin to clear as it is driven out of the aligned holes. In practice the rivet serves as a very useful form of a holding means and may be readily applied to a chain without changing the design or construction of the chain.

In Figures 11 and 12, the bushing 31 has a notch 32 in the upper edge thereof and as the holding rivet 24 is upset a small portion 33 is caused to protrude into the notch 32 to keep the bushing 31 from turning with reference to the pin 23. In this embodiment, no relative movement occurs between the pin 23 and the bushing 31, and thus relative movement is caused to take place between the bushing and the opening 30 in the eye-portion 20. This arrangement is useful in certain fields of application.

In Figures 13 to 19, I show a modification of my invention in that the pin 34 has no head, but is provided with a key-way 35 in the side thereof to receive a square shouldered head 37 of the holding rivet 36. The head 37 of the rivet has a flat side 38 and allows the pin 34 to be inserted in the hinge connection, as shown in Figure 13. When the inserted key-way 35 becomes in register with the head 37 of the rivet, the rivet is rotated substantially one-quarter of a turn as shown in Figure 14 to lock or key the pin 34 in position. The holding rivet 36 is then upset as shown in Figure 15, with a portion of the upset rivet overlapping the recess 39 in the pin 34 which keeps the pin from rotating. The head 37 of the holding rivet 36 locks or keys the pin 34 against endwise movement.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In combination with a member having a first and a second side and having a main opening extending therethrough from one side to the other and a pin fitting in the main opening with an exposed end of the pin lying substantially flush with the first side of the member, the said member also having adjacent one side of the main opening a secondary opening forming a bay therewith, of holding means to oppose disengagement of the pin from the main opening, said holding means including a rivet having a head engaging the second side of the member in the vicinity of the secondary opening and having a stem passing through the secondary opening and disposed adjacent the pin, said stem of the rivet being upset and overlapping a portion of the first side of the member and a portion of the exposed end of the pin to oppose disengagement of the pin from the main opening.
2. In combination with a member having a

first and a second side and having a main opening extending therethrough from one side to the other and a pin fitting in the main opening with an exposed end of the pin lying substantially flush with the first side of the member, the said member also having adjacent one side of the main opening a secondary opening forming a bay therewith, a holding means to oppose disengagement of the pin from the main opening, said holding means including a rivet having a head engaging the second side of the member in the vicinity of the secondary opening and having a stem passing through the secondary opening and disposed adjacent to the pin, said stem of the rivet being upset and overlapping a portion of the first side of the member and a portion of the exposed end of the pin to oppose disengagement of the pin from the main opening, the second side of the member in the vicinity of the secondary opening being recessed to receive the head of the rivet and the first side of the member and said exposed end of the pin being jointly recessed to receive the upset end of the stem of the rivet.

3. In a chain having pivotally connected elements connected together by a pin, said pivotally connected elements having main openings aligned with each other through which the pin passes, one of said elements of the chain including a member having a first and a second side, said pin having an exposed end lying substantially flush with the first side of the member, the said member also having adjacent one side of the main opening a secondary opening forming a bay therewith, of holding means to oppose disengagement of the pin from the main opening, said holding means including a rivet having a head engaging the second side of the member in the vicinity of the opening and having a stem passing through the secondary opening and disposed adjacent to the pin, said stem of the rivet being upset and overlapping a portion of the first side of the member and a portion of the exposed end of the pin to oppose disengagement of the pin from the main openings.

4. In a chain having pivotally connected elements connected together by a pin, said pivotally connected elements having main openings aligned with each other through which the pin passes, one of said elements of the chain including a member having a first and a second side, said pin having an exposed end lying substantially flush with the first side of the member, the said member also having adjacent one side of the main opening a secondary opening forming a bay therewith, of holding means to oppose disengagement of the pin from the main opening, said holding means including a rivet having a head engaging the second side of the member in the vicinity of the opening and having a stem passing through the secondary opening and disposed adjacent to the pin, said stem of the rivet being

upset and overlapping a portion of the first side of the member and a portion of the exposed end of the pin to oppose disengagement of the pin from the main openings, the other of said elements of the chain having a bearing fitting in the main opening thereof and surrounding the pin, said bearing being free to rotate about the pin and in the main opening of the said other of said elements, said pin being snugly pressed in the main openings of the said one of said elements.

5. In a chain having pivotally connected elements connected together by a pin, said pivotally connected elements having main openings aligned with each other through which the pin passes, one of said elements of the chain including a member having a first and a second side, said pin having an exposed end lying substantially flush with the first side of the member, the said member also having adjacent one side of the main opening a secondary opening forming a bay therewith, of holding means to oppose disengagement of the pin from the main opening, said holding means including a rivet having a head engaging the second side of the member in the vicinity of the opening and having a stem passing through the secondary opening and disposed adjacent to the pin, said stem of the rivet being upset and overlapping a portion of the first side of the member and a portion of the exposed end of the pin to oppose disengagement of the pin from the main openings, said pin having a keyway to receive the head of the rivet.

6. In a chain having pivotally connected elements connected together by a pin, said pivotally connected elements having main openings aligned with each other through which the pin passes, one of said elements of the chain including a member having a first and a second side, said pin having an exposed end lying substantially flush with the first side of the member, the said member also having adjacent one side of the main opening a secondary opening forming a bay therewith, of holding means to oppose disengagement of the pin from the main opening, said holding means including a rivet having a head engaging the second side of the member in the vicinity of the opening and having a stem passing through the secondary opening and disposed adjacent to the pin, said stem of the rivet being upset and overlapping a portion of the first side of the member and a portion of the exposed end of the pin to oppose disengagement of the pin from the main openings, the other of said elements of the chain having a bushing fitting in the main opening thereof and surrounding the pin, said bushing having a notch to receive an upset portion of the rivet to keep the bushing from turning with reference to the pin.
